UNITED STATES PATENT OFFICE.

PETER MALEWIG AND JOSEPH WALLACE, OF CHICAGO, ILLINOIS.

TYPOGRAPHIC NUMBERING MACHINE.

Application filed September 23, 1922. Serial No. 590,182.

To all whom it may concern:

Be it known that we, PETER MALEWIG and JOSEPH WALLACE, both citizens of the United States, and residents of the city of Chicago, in the county of Cook and State of Illinois, have invented certain new and useful Improvements in a Typographic Numbering Machine; and we do hereby declare that the following is a full, clear, and exact description of the same, reference being had to the accompanying drawings, and to the numerals of reference marked thereon, which form a part of this specification.

This invention relates to improvements in typographic numbering machines, with special reference to reducing the cost of assembly and repair thereof by improvements embodied in the main frame and ratchets.

Heretofore, numbering machines intended to be set up with type in forms for consecutively numbering checks and other work of such a character have been constructed with a solid frame that renders such a machine very difficult to assemble, because of the multiplicity of parts which must go together at the same time in definite relationship to each other.

It is an important object of this invention to provide a main frame construction permitting a unit or sub-assembly of the many intricate parts entering into the construction of a typographic numbering machine.

It is a further important object of this invention to render the several sub-assemblies mentioned above capable of rapid final assembly by other than highly skilled workmen so that users of such devices may themselves disassemble the machine for cleaning or repairing with assurance that they will be able to put the various parts together correctly.

It is another object of this invention to retain the ratchets in proper spaced relation to the number wheels so that removal of the wheels will not permit the ratchets to be displaced and consequently be a source of difficulty in properly reassembling the wheels in the frame.

Other and further important objects of

this invention will be apparent from the disclosures in the drawings and the accompanying specification.

The invention (in a preferred form) is illustrated on drawings and hereinafter more fully described.

On the drawings:

Fig. 1 is a fragmentary view of a type case containing a typographic numbering machine embodying the improved features of this invention.

Fig. 2 is an end perspective drawing of the main frame of such a numbering machine.

Fig. 3 is an end view of such a machine with the plunger mechanism omitted.

Fig. 4 is a side elevation of this device with parts omitted.

Fig. 5 is a section on the line 5—5 of Fig. 3 with parts omitted.

Fig. 6 is a perspective drawing of a numbering wheel shaft.

As shown on the drawings:

The preferred form of this invention relates to plunger actuated numbering machines of well known construction, the various parts of which are standard except for the main frame, ratchet spacing and wheel shaft described in detail hereinafter.

The usual construction of such typographic consecutive numbering machines embraces a main frame 1, which will be described more in detail hereinafter, having extending sides 2 with jaws 3 for retaining a casing 4 holding a plunger 5 which actuates through a connection 6 a pawl swing 7 and spring pressed pawls 8 which operate to cause consecutive action, in a manner well known in the art, of a plurality of number wheels 9 rotatable on a wheel shaft 10 on the return stroke of the plunger after making an impression. The number wheels are retained in register by a plurality of spring finger pressed ratchets 11 with a heavier similar ratchet 12 held into engagement with the index or first wheel by a torsion spring 13. In the particular form of mechanism shown the wheel shaft has an angular depression milled out along its length and the intermediate number wheels have movable

2

ciphers which can drop into this depression to prevent printing thereof when no significant number is present to the left of said ciphers.

5 The main frame 1 of this invention comprises a split hingedly connected case for the various parts of the machine. The two parts comprising the frame are provided with integrally formed pivots 14 and dowel pins 15 10 are also provided so that the closed frame has the rigidity of a solid frame.

The ratchets 11 and 12 are mounted on a rod 16 inserted through holes 17 in one member of the frame, and are retained in correctly spaced relation to each other by means of bushings or spacers 18 on said rod between the ratchets. It has been found that this improvement eliminates all the previously mentioned difficulty in assembling the number wheels in the main frame. 20

The wheel shaft 10 is provided with a square head 19 and a dowel 20 seating in suitable apertures 21 in the main frame to bring the angular depression in the shaft into proper position relative to the printing side of the frame.

The assembly of a mechanism embodying the improvements which form the subject matter of this invention is much simpler than with the former construction. The number wheels, pawl swing and wheel shaft can be assembled with comparatively little trouble when separate from the frame, and the ratchets and bushings can be assembled 35 into the split main frame with similar comparative ease. Next the wheel and pawl assembly can be placed in the split frame with the dowel 20 registering with its aperture in the frame when the frame may be closed, and the connection 6 and plunger and casing added and held in place in the jaws provided therefor on the main frame. 40

We claim as our invention:

1. In a numbering machine, a set of printing number wheels, mechanism for actuating said wheels to bring the numerals in proper order into position at the printing face of the device and a frame for housing and supporting said mechanism, said frame including two pairs of end members, one pair at each end of the frame, the members of each pair being pivoted together adjacent the printing face of the device. 50

2. In a numbering machine, a set of printing number wheels, mechanism for actuating said wheels to bring the numerals in proper order into position at the printing face of the device and a frame for housing and supporting said mechanism, said frame including two pairs of end members, one pair at each end of the frame, the members of each pair being pivoted together adjacent the printing face of the device, said frame connecting the end members at only 60 the corners opposite said printing face. 65

3. In a numbering machine, a set of printing number wheels, mechanism for actuating said wheels to bring the numerals in proper order into position at the printing face of the device, a plunger for operating said mechanism, a frame for housing and supporting said mechanism, said frame including two pairs of end members, one pair at each end of the frame, the members of each pair being pivoted together adjacent the printing face of the device, flanges one on each of one pair of said end members, a casing for said plunger and means for securing said casing between said flanges. 70 75

4. In a numbering machine, a set of printing number wheels, mechanism for actuating said wheels to bring the numerals in proper order into position at the printing face of the device, a frame for housing and supporting said mechanism, said frame including two pairs of end members, one pair at each end of the frame, the members of each pair being pivoted together adjacent the printing face of the device and a dowel pin on one member of each pair the other member of each pair having a co-operating dowel hole, said pins and holes being adjacent the side of the device opposite the printing face. 80 85 90

5. In a numbering machine, a set of printing number wheels, a common shaft for said wheels, mechanism for actuating said wheels to bring the numerals in proper order into position at the printing face of the device and a frame for housing and supporting said mechanism, said frame including two pairs of end members, one pair at each end of the frame, the members of each pair being pivoted together adjacent the printing face of the device, the end members at one end having recesses at their meeting edges which register to form a non-circular hole when the frame is closed, the other pair of end members which form a circular hole, said holes being suitably located to receive the ends of said shaft and said shaft having a non-circular head at one end to fit said non-circular hole. 95 100 105

6. In a numbering machine, a set of printing number wheels, a common shaft for said wheels, mechanism for actuating said wheels to bring the numerals in proper order into position at the printing face of the device, a frame for housing and supporting said mechanism, said frame including two pairs of end members, one pair at each end of the frame, the members of each pair being pivoted together adjacent the printing face of the device, the end members at one end having recesses at their meeting edges which register to form a non-circular hole when the frame is closed, the other pair of end members which form a circular hole, said holes being suitably located to receive the ends of said shaft and said shaft having a non- 110 115 120 125 130

circular head at one end to fit said non-circular hole, said shaft having a groove therein, one of said end members having a dowel hole at the bottom of its non-circular recess and a dowel pin on said head positioned to enter said dowel hole when said groove is toward the printing face of the device.

In testimony whereof, we have hereunto subscribed our names in the presence of two 10 subscribing witnesses.

PETER MALEWIG.
JOSEPH WALLACE.
